United States Patent

Des. 240,983
Patented Aug. 17, 1976

240,983

DISPLAY STAND

Philip J. Rowman, Hillsboro Park, Derry Road,
Hudson, N.H. 03051

Filed June 4, 1973, Ser. No. 366,412

Term of patent 14 years

Int. Cl. D6—03; D20—02

U.S. Cl. D6—27

Fig. 1.

Fig. 2.

Fig. 4.

Fig. 3.

FIG. 1 is a top plan view of a display stand, embodying my new design;

FIG. 2 is a side elevational view thereof from one side, the view from the other side being identical therewith;

FIG. 3 is a bottom elevational view of a display stand; and

FIG. 4 is a perspective view showing two sides, the other two sides being identical in appearance therewith. I claim:

The ornamental design for a display stand, substantially as shown and described.
